UNITED STATES PATENT OFFICE.

TOM MORRISON, OF TOLEDO, OHIO, ASSIGNOR OF ONE-HALF TO MAURICE SHUER AND ABRAHAM HATTNER, BOTH OF TOLEDO, OHIO.

SELF-HEATING TOOL FOR ASPHALT PAVEMENTS.

Application filed October 10, 1921. Serial No. 506,708.

To all whom it may concern:

Be it known that I, TOM MORRISON, citizen of the United States, residing at Toledo, in the county of Lucas and State of Ohio, 5 have invented new and useful Improvements in Self-Heating Tools for Asphalt Pavements, of which the following is a specification.

This invention relates to self-heating tools 10 for use in tamping and smoothing asphalt when laying pavements.

The object is to provide particular means for continuously applying heat, so that the tools may be kept at a uniform temperature, 15 and the loss of time incident to heating the implements in the usual way may be avoided.

A further object is to provide a heating element or elements which may be applied with little change in construction to either 20 a tamping or a smoothing device.

A still further object is to provide a tool which shall include a hollow body having a removable cover, the heating element or elements being mounted in part on the under 25 side of the cover, and the fuel supply devices and handle being detachable, if desired.

A still further object is to provide, in connection with a hollow body and a burner or plurality of burners mounted therein,—a detachable handle for said body, the handle carrying fuel and air supply devices, and means being provided for detachably connecting these devices with the valved ducts leading to the burners. 30

With the foregoing and other objects in view, the invention consists in the novel construction and arrangement of elements described and claimed, it being understood that modifications may be made within the scope 35 of the claims, without departing from the spirit of the invention.

Fig. 1, discloses a side elevation of the self heating tool.

Fig. 2, is a rear view.

Fig. 3, is a longitudinal section.

Fig. 4, is a top plan view of the tamping device.

Fig. 5, is a side elevation of a modified form of my device.

Fig. 6, is a longitudinal section through the structure disclosed in Fig. 5.

The tamping device includes the hollow body 10 having a bottom 11 the upper surface of which may be provided with ribs 12. 50

The sides 13 and 14 are cut away as shown

at 15 and 16, and the top 18 is formed with a central transverse opening 19 having communication with the channeled portion 20 formed on or carried by the under side of the cover. 60

A socket member 21 carried by the cover receives the end of handle 22, the latter being retained by set screw or thumb screw 23. The cover is detachably retained on the hollow body 10 by threaded elements 24 engaged by nuts 25. 65

Mounted on the handle is a gasoline tank 26 having a filling opening closed by a plug or cap 28, and a pipe 29 leading from the tank is provided with a valve 30. A union or coupling 31 connects pipe 29 with the three-way connection 33 in communication with valve casing 35, mounted on a ledge 37 on body 10. Needle valves 38 are controlled by valve wheels 39, and the nozzles 40 pass through apertures in the channeled member 20 on the lower side of the cover. 70

The burner 42, is of the form shown, and includes an upper portion, a lower perforated portion, and an upturned end portion 44, located as illustrated with reference to the feed. The upper portions of the burner enter apertures in channeled member 20 at points opposite the nozzles 40, air being supplied through the opening 19 in the cover. Air enters the body 10 through the openings in the side walls thereof. An air pump 45 is mounted on the handle and connected therewith is a section of hose of flexible tubing. 75

The smoothing tool includes a body 10' having a bottom 11' the under side of which is curved as shown, the body being elongated, and the socket member 21' being carried directly by the body. The detachable top 18' has an air opening 19' and also an opening 11^a closed by a cover 11^b, permitting access to the burners. The other elements correspond in general, both in function and construction, with those described in connection with the first form. Similar reference numbers are employed, the numbers being primed in order to make the relation clear. A pivoted support 48 holds the handle in proper position when the workman releases it, and when the support is not needed it is held by engaging device 49 secured to the handle. 80

What I claim is—
1. In a device of the class described, a hollow body, a cover therefor, a burner and 85

110

means for mounting the latter within the hollow body in position for directing flame into contact with the upper surface of the bottom of said body, and means for supplying fuel to the burner, said hollow body having a rounded bottom, a handle extending laterally from the body, and a pivoted foldable member for supporting the handle in position for maintaining the body substantially level.

2. In a device of the class described, a hollow body for application to hot asphalt in laying pavements, a cover for said body, a socket member carried by the cover, an opening being provided transversely of the

cover and socket member and affording an air inlet, a portion depending from the lower side of the cover and having a transverse channel communicating with the transverse opening, and a burner having an upper open end extending into the depending portion, a valve controlled fuel nozzle opposite said upper open end, the burner having a perforated portion adjacent to the bottom of the hollow body, said perforated portion extending to a point adjacent to the point of admission of liquid fuel to the nozzle.

In testimony whereof I affix my signature.

TOM MORRISON.
